LOCOMOTIVE FRONT END CONSTRUCTION

Eugene L. Schellens, Ridgewood, N. J., assignor
to C-S Engineering Company, Englewood, N. J.,
a corporation of Delaware

Application December 19, 1929, Serial No. 415,199

16 Claims. (Cl. 110—122)

This invention relates to the drafting of locomotives, and more particularly to locomotive front end construction, and has three primary objects in view, to wit: the thorough removal of cinders from the locomotive exhaust gases, the substantial increasing of draft efficiency, and the provision of a rugged, compact, and unified structure to accomplish both of said ends.

More particularly, the invention involves the separation of cinders and dust from the gases as the latter pass from the flues to the stack, the collection of the separated solids, the returning of them to the firebox or ashpan, the elimination of cinder netting, screens and other troublesome elements in the smokebox, the increasing of draft intensity and efficiency while at the same time keeping the cinders away from the point of maximum vacuum, and in general the provision of a simple and rugged device which will accomplish the aforesaid purposes and at the same time co-operate with the ordinary arrangement of smokebox, flue sheet, superheater header and steam pipes.

Specifically, the invention contemplates the provision, in a locomotive smokebox, of an internal draft chamber within the smokebox and surrounding the stack and nozzle-tip, the elongation and extension of the stack downwardly to a point near the bottom of the smokebox, means co-operating with the wall of said chamber to provide curved passages therearound for the guidance of the gases and cinders from the superheater chamber behind the stack to the cinder-collecting chamber in front thereof, means co-operating with the aforesaid means to divert the solids forwardly away from the draft chamber and to reverse the flow of gases rearwardly into said chamber and up the stack, means for collecting said solids and means for continuously re-turning them to a part of the firebox.

The invention further contemplates certain constructional features of advantage as will hereinafter appear.

How the foregoing, together with such other objects and advantages as are incident to the invention or will occur to those skilled in the art, are obtained by my invention will appear from the following description, taken together with the accompanying drawings which illustrate one embodiment of the invention, and in which drawings

Figure 1 is a vertical longitudinal section through a locomotive front end construction embodying my invention, certain parts being shown in elevation;

Figure 2 is a transverse section on the line 2—2 of Fig. 1;

Figure 3 is a horizontal mid-section on the line 3—3 of Fig. 1;

Figure 4 is a section, on the line 4—4 of Fig. 1, of one part of the structure only;

Figure 5 is a section of the same part, on the line 5—5 of Fig. 1; and

Figure 6 is a somewhat diagrammatic, broken-away, side elevational view of the locomotive structure, the front end of which is shown in Fig. 1.

Referring first to Figs. 1 and 6, it will be seen that I have illustrated a locomotive boiler 2 having a front end or smokebox 3, smokebox cover 10 15 4, firebox and ashpan 5, 6, stack outlet 7, exhaust-tip 8, front flue sheet 9, flues 10, superheater compartment 11, dry-pipe 12, superheater header 13, superheater damper 14, superheater elements 15, and steam pipes 16 (only one of which is shown, 20 although it will be understood that there is usually one on each side of the stack leading from the header to the steam-chest on the respective side of the locomotive), only such portions of these ordinary locomotive parts being illustrated as are necessary to an understanding of the present invention.

Surrounding the stack 7a, which I have extended downwardly inside the smokebox much farther than is the usual practice, so that its inlet end or throat 7b is near the exhaust-tip 8 and not far from the bottom 3a of the smokebox shell, is a wall or partition 17 forming an inner draft or vacuum chamber 18 around the stack. This partition wall 17 is, roughly, in the form of a vertical cylinder, extending from top to bottom of the smokebox, although it is preferably enlarged in diameter toward the bottom; the relative shapes and cross-sectional areas of its upper and lower ends 17a, 17b, being illustrated in Figs. 1, 4 25 and 5. In its mid-portion it has a vertically-elongated opening 17c, at the front (seen best in Figs. 2 and 3).

Extending forwardly and inwardly, from the sides, 3b, 3b, of the smokebox (as seen in Fig. 3) 45 are a pair of partition walls or guiding members 19, substantially vertically disposed, which are curved or of arcuate contour as at 19a to co-operate with the outer surface of draft-chamber wall 17 to form curved passageways 20 for the products of combustion, these passages being defined at top and bottom by the top closure walls 19b and the bottom of the smokebox, respectively. The passageways 20 are thus located laterally at 50 each side of the central stack and draft chamber,

as seen in Figure 3. Forwardly and outside of the partitions 19, 19a, is a cinder and dust chamber or space 21 (seen in Figs. 1 and 3) beneath which is a collector or pocket 22 for such solids.

5 In the opening 17c through the front wall of partition 17, I preferably provide a vertical deflector or guiding baffle device 23, which may be flared outwardly and rearwardly at each side, as at 23a, 23a, such deflector being supported between the upper edge 24 and the lower edge 25 of said opening; and it should be observed that said lower edge 25 is preferably positioned above the inlet end 7b of the stack.

10 As will be seen in Figs. 1 and 2, the cinder hopper or collector 22 is preferably laterally extended at the bottom, so that the rearwardly-extending cinder disposal pipe 26 will clear the saddle structure 27. Whenever the locomotive is running, there is a constant discharge of the cinders and dust from the collecting chamber through pipe 26 into the firebox, adjacent the grate or ashpan (as shown in Fig. 6) by means of the jet device shown in Figs. 1, 2, and 6. Said jet device may conveniently comprise a jet nozzle 15 or tip 28, directed through the front wall of chamber 22 and extending in axial alignment with the pipe 26 (which preferably is so positioned as to extend in a straight line to the firebox 5), and a small steam pipe 29 which may readily be connected, outside the smokebox, to the steam pipe 16, so that whenever steam is going to the cylinders there will be a continuous removal of cinders from the collector, by means of the steam jet.

15 In operation, it will now be seen that the exhaust from the tip 8, passing out through the stack 7a, 7, creates a high vacuum in the inner chamber 18 which induces a heavy draft through the curved passages 20, 20 (said passages communicating with said chamber 18 through the forward opening 17c, and with the flues 10 at the back by way of the superheater chamber 11). The curved passages 20 are of considerable length from back to front and are so proportioned and of such contour that the products of combustion 20 are drawn through them with great velocity. The centrifugal force thus set up acts upon the solids, which are carried in suspension in the gases, and causes them to follow closely the inner surface of the portions 19a of the guiding walls 19 and to be ejected violently into the cinder chamber 21 whence they drop into the hopper 22.

25 At the same time, the gases and very light solids are caused by the draft to undergo a sudden change of direction in order to pass back into the inner chamber 18 and thence to the stack. This reversal of the gas stream is facilitated by the baffle means 23, which at the same time serves to deflect outwardly into the chamber 21 any of the solid particles or cinders which may tend to follow with the gases upon the reversal of flow of the latter. The substantial length of the curved passages 20 provides a relatively great time element for the passage of the products of combustion therethrough, which ensures that the cinders shall be closely following the surface of the partitioning 19a by the time they leave the passages 20, so that there is very nearly perfect separation of the cinders from the gases.

30 By my construction, I not only eliminate the necessity for the usual netting, apron, table plate, etc., which are troublesome and inefficient, but also take advantage of this by extending the stack downwardly, (as hereinbefore briefly referred to) for, it should be understood, in the ordinary smokebox construction the table-plate is located

approximately at the level of the bottom of my stack, or even higher, the nozzle-tip must extend above the table-plate, and the bottom of the stack must be placed still higher. By my invention, on the other hand, the nozzle-tip 8 is 5 preferably placed adjacent the bottom 3a of the smokebox, and the stack is extended downwardly so that its total length is approximately 40% greater than the length of the ordinary stack for the same locomotive. I thereby obtain a 10 much greater range for proportioning the elements of stack length, stack diameter, nozzle characteristics, and spacing between nozzle-tip and stack throat; and I have found that the proportions about as I have indicated them in the 15 drawings, with stack length about 40% more than usual, produce a much higher draft efficiency.

20 A further substantial advantage is attained as follows: by extending the stack inlet 7b down to the point shown (see Figs. 1 and 2) and by positioning the lower edge 25 of the opening 17c above the bottom of the stack, the path of travel of the cinders is effectively kept separate from the point of greatest draft intensity, i. e. the throat of the stack, and the gases which pass 25 through the lower portions of passages 20 must pass upwardly and over the edge 25 to reach the inner, or draft chamber.

25 From the foregoing it is evident that my invention attains its stated objects in a simple and effective manner; that cinders are separated, collected and removed without the aid of any moving parts; that the intensity and efficiency of the draft are increased, and this without any tendency to carry off sparks through the stack; that inherently a much greater range for proportioning the draft parts is provided; and that all of these ends are served by a unified and rugged structure which cannot get out of order, requires practically no maintenance, eliminates troublesome parts heretofore used, and co-operates with and fits neatly into the general smokebox arrangement.

30 I claim:—

35 1. In a locomotive, a smokebox, a stack, partition means providing an inner draft chamber around said stack, and guiding means outside of said partition means curved about an axis substantially paralleling the stack axis to cooperate with said partition means to form a curved passage way for the products of combustion, said partition and said guiding means being apertured, and the bottom of the aperture through the partition being higher than the bottom of the aperture through said guiding means.

40 2. Locomotive front end construction including a smokebox, draft creating means, and a stack extending into the smokebox, a shell forming an inner draft chamber peripherally surrounding the stack and having an opening in the front, gas 45 passage means surrounding said chamber and having an opening in the front, and means forming a cinder chamber in front of said openings.

45 3. Locomotive front end construction including a smokebox, draft creating jet means, and a stack extending into the smokebox in line with said jet means, an inner draft chamber surrounding the stack and having an opening in the front, gas 50 passage means surrounding said chamber and having an opening in the front, and a cinder chamber in front of said openings, said stack extending below the first of said openings.

55 4. Locomotive front end construction including a smokebox, draft creating jet means adjacent the bottom of the smokebox, and a stack extend- 55

ing into the smokebox in line with said jet means, an inner draft chamber surrounding the stack and having an opening in the front, gas passage means surrounding said chamber and having an opening in the front, and a cinder chamber in front of said openings, said stack extending below the first of said openings to a zone adjacent the bottom of the smokebox.

5. In combination with a smokebox, a stack, a shell forming a draft chamber in the box peripherally around the stack and having an opening in front of the stack, means forming an elongated curved passageway extending generally horizontally around said chamber and stack laterally thereof and opening at the front, and part of the smokebox structure forming a cinder space in front of the said means.

6. In combination with a smokebox, a stack, a draft chamber in the box and around the stack, and having an opening in front of the stack, means forming an elongated curved passageway around said chamber and stack, opening at the front, and smokebox structure forming a cinder space in front of the said means, said stack extending down below said first opening.

7. In a locomotive, a smokebox, a stack, baffle means forwardly of the stack including generally upright baffle walls having an opening therethrough toward the front of the locomotive to provide a cinder collecting chamber disposed forwardly of such upright walls, additional baffle means including generally upright walls positioned to define an upright draft chamber generally axially of said stack, the upright walls of said additional baffle means being apertured toward the front thereof, and the two baffle means being arranged to provide a gas passage therebetween, whereby the products of combustion are directed forwardly through said passage, thence rearwardly into said draft chamber and finally upwardly for discharge from the stack and whereby cinders are projected forwardly into the cinder chamber out of the path of travel of the gases in the zone at which the gases enter said draft chamber.

8. In a locomotive, a smokebox, a stack having its lower end portion extended into the smokebox, partition means positioned circumferentially about said portion of the stack to provide an inner draft chamber around said portion, and guiding means outside of said partition means curved about an axis substantially paralleling the stack axis to effect a circuitous flow of the gases to said inner chamber and apertured to effect centrifugal discharge of cinders and the like from the gas stream.

9. In a locomotive, a smokebox, a stack having its lower end portion extended into the smokebox, partition means positioned circumferentially about said portion of the stack to provide an inner chamber around said portion, guiding means outside of said partition means curved on an axis substantially paralleling the stack axis to effect a circuitous flow of the gases to said inner chamber and apertured to effect centrifugal discharge of cinders and the like from the gas stream, and a cinder receiving chamber in position to receive the discharged cinders, said guiding means cooperating with the smokebox itself to form said receiving chamber.

10. In a locomotive having a smokebox space and an upright exhaust or outlet stack associated therewith, a drafting and cinder handling assembly comprising an upstanding approximately cylindrical shell or vertically extending housing

structure in the smokebox forming a chamber of less diameter than the maximum transverse width of the smokebox space, a downward prolongation of said stack extending an appreciable distance into said chamber and in communication therewith, a draft forcing device extending upwardly into the bottom of the chamber and in communication therewith and having an outlet in substantial alinement with the stack extension, said shell being substantially closed at the top and bottom except for said communications and having a vertically elongated apertured area or opening in the front portion thereof, and means forming for the products of combustion a passageway adjacent the lower portion of said shell extending from behind the shell to the front thereof, whereby the stream or flow of the combustion gases abruptly reverses its direction and then back through the opening into the interior of the shell.

11. In a locomotive having a smokebox space and an upright exhaust or outlet stack associated therewith, a drafting and cinder handling assembly comprising an upstanding approximately cylindrical shell or vertically extending housing structure in the smokebox forming a chamber of less diameter than the maximum transverse width of the smokebox space, a downward prolongation of said stack extending an appreciable distance into said chamber and in communication therewith, a draft forcing device extending upwardly into the bottom of the chamber and in communication therewith and having an outlet in substantial alinement with the stack extension, said shell being substantially closed at the top and bottom except for said communications and having a vertically elongated apertured area or opening in the front portion thereof, and means forming for the products of combustion a passageway extending from behind the shell to the front thereof, whereby the stream or flow of the combustion gases abruptly reverses its direction by passing forwardly through said passageway and then back through the opening into the interior of the shell, and vertical deflector plate means associated with said opening.

12. In a locomotive having a smokebox space and an upright exhaust or outlet stack associated therewith, a drafting and cinder handling assembly comprising an upstanding approximately cylindrical shell or vertically extending housing structure in the smokebox forming a chamber of less diameter than the maximum transverse width of the smokebox space, a downward prolongation of said stack extending an appreciable distance into said chamber and in communication therewith, a draft forcing device extending upwardly into the bottom of the chamber and in communication therewith and having an outlet in substantial alinement with the stack extension, said shell being substantially closed at the top and bottom except for said communications and having a vertically elongated apertured area or opening in the front portion thereof, and means forming for the products of combustion a passageway extending from behind the shell to the front thereof, whereby the stream or flow of the combustion gases abruptly reverses its direction by passing forwardly through said passageway and then back through the opening into the interior of the shell, and vertically extending transversely-curved deflector plate means associated with said opening.

13. In a locomotive having a smokebox space and an upright exhaust or outlet stack associated

- therewith, a drafting and cinder handling assembly comprising an upstanding approximately cylindrical shell or vertically extending housing structure in the smokebox forming a chamber of less diameter than the maximum transverse width of the smokebox space, a downward prolongation of said stack extending an appreciable distance into said chamber and in communication therewith, a draft forcing device extending upwardly into the bottom of the chamber and in communication therewith and having an outlet in substantial alinement with the stack extension, said shell having an opening formed in a part of its peripheral wall for ingress of the exhaust gas stream and means forming a peripherally enclosed well or pocket adjacent the bottom of the chamber in surrounding relation to the outlet of the draft forcing device and subjacent to the bottom of the stack extension.
14. In a locomotive having a smokebox space and an upright exhaust or outlet stack associated therewith, a drafting and cinder handling assembly comprising an upstanding approximately cylindrical shell or vertically extending housing structure in the smokebox forming a chamber of less diameter than the maximum transverse width of the smokebox space, a downward prolongation of said stack extending an appreciable distance into said chamber and in communication therewith, a draft forcing device extending upwardly into the bottom of the chamber and in communication therewith and having an outlet in substantial alinement with the stack extension, said shell having an opening formed in a part of its peripheral wall for ingress of the exhaust gas stream, means forming a peripherally enclosed well or pocket adjacent the bottom of the chamber in surrounding relation to the outlet of the draft forcing device and subjacent to the bottom of the stack extension, and means associated with said shell for tangentially diverting solids such as heavy cinders from the immediate zone of the draft.
15. In a locomotive having a smokebox space and an upright exhaust or outlet stack associated therewith, a drafting and cinder handling assem-

bly comprising an upstanding approximately cylindrical shell or vertically extending housing structure in the smokebox forming a chamber of less diameter than the maximum transverse width of the smokebox space, a downward prolongation of said stack extending an appreciable distance into said chamber and in communication therewith, a draft forcing device extending upwardly into the bottom of the chamber and in communication therewith and having an outlet in substantial alinement with the stack extension, said shell having an opening formed in a part of its peripheral wall for ingress of the exhaust gas stream, means forming a peripherally enclosed well or pocket adjacent the bottom of the chamber in surrounding relation to the outlet of the draft forcing device and subjacent to the bottom of the stack extension, and upstanding plate means associated with said opening.

16. In a locomotive having a smokebox space and an upright exhaust or outlet stack associated therewith, a drafting and cinder handling assembly comprising an upstanding approximately cylindrical shell or vertically extending housing structure in the smokebox forming a chamber of less diameter than the maximum transverse width of the smokebox space, a downward prolongation of said stack extending an appreciable distance into said chamber and in communication therewith, a draft forcing device extending upwardly into the bottom of the chamber and in communication therewith and having an outlet in substantial alinement with the stack extension, said shell having an opening formed in a part of its peripheral wall for ingress of the exhaust gas stream, means forming a peripherally enclosed well or pocket adjacent the bottom of the chamber in surrounding relation to the outlet of the draft forcing device and subjacent to the bottom of the stack extension, upstanding plate means associated with said opening, said opening being at the front of said shell, and means forming a gas flow passage from behind the shell to the front thereof for reverse bending of said gas flow backward into said opening.
